UNITED STATES PATENT OFFICE.

CLARENCE F. STEWART, OF NORWALK, OHIO.

MACHINE FOR MAKING DOWEL-PINS.

SPECIFICATION forming part of Letters Patent No. 351,292, dated October 19, 1886.

Application filed May 24, 1886. Serial No. 203,094. (No model.)

To all whom it may concern:

Be it known that I, CLARENCE F. STEWART, of Norwalk, in the county of Huron and State of Ohio, have invented certain new and useful Improvements in Machines for Making Dowel Pins; and I do hereby declare the following to be a full, clear, and exact description of the invention, such as will enable others skilled in the art to which it pertains to make and use the same.

My invention relates to improvements in machines for making dowel-pins; and it consists in certain features of construction and in combination of parts hereinafter described, and pointed out in the claims.

In the manufacture of dowel-pins the wood is cut into blocks of suitable length, and the blocks are split into "rives" of suitable thickness, and these latter are fed, usually by hand, into a machine, where a reciprocating plunger forces the timber against the splitting-knife, severing the blank that is forced through a finishing-die. Heretofore a gage adjusted in suitable position has usually been rigidly attached to the bed, and the splitting-knife was arranged somewhat oblique to the line of the gage to give sufficient clearance for the blank in case the wood should not split straight, the wood being held down by a spring. With such construction, in case the wood did split straight, by means of the aforesaid clearance the block was likely to be turned to the one side and enter the finishing-die obliquely, by reason of which many blanks were spoiled. As an improvement I set the splitting-knife parallel with the axial line of the finishing-die and provide a yielding guide-block rabbeted along the inner lower corner to engage the blank on the rear and top sides. Springs are arranged to press the guide-block downward and forward, by means of which the blank is always firmly held against the knife and against the bed and made to enter straight into the finishing-die.

In the accompanying drawings, Figure 1 is a side elevation of a machine embodying my invention. Fig. 2 is a top plan partly in section. Fig. 3 is an elevation in section on the line of $x-x$, Fig. 1. Fig. 4 is an elevation in section on the line of $y-y$, Fig. 2. Fig. 5 is a rear elevation of the guide-block.

A represents the bed-plate, the same hav-

ing suitable ways, A', in which operates a reciprocating plunger, B, a crank and pitman (not shown) or other suitable mechanism being had for operating the plunger.

C is the splitting-knife, the shank of which fits in the recess a of the bed. The knife is secured by a bolt, c , that passes through the bed and through an arm, D, securing the latter, the arm being seated in a recess, a' , of the bed, as shown in Fig. 2.

E is a guide-block having an arm, E', pivoted at a' to the bed-plate. The arm E' is made thin laterally, so as to be somewhat elastic. The block E is rabbeted along the lower corner on the front side, at e , so as to engage the blank on the top and rear sides. Springs e' , preferably of rubber, are backed preferably by cap-shaped washers e'' , adjustably secured by screws e''' , that engage threaded holes in the arm D. One spring is made to press the block E downward toward the bed, and the other spring is made to press the block forward toward the knife. The knife C stands at right angles to the face of the bed, with the rear side of the knife set parallel with the axial lines of the die H. By reason of the guide-block E and springs aforesaid, the blank is held firmly against the knife and against the bed, and is thus guided straight into the die.

F is a flange projecting upwardly from the bed, and at right angles to the latter, both laterally and vertically. The flange is more conveniently cast onto the bed-plate, but may be made separately, if preferred, and bolted or otherwise secured to the bed. The flange has an opening, f , for the passage of the dowel-pin, and vertical slots f' , through which latter pass the securing-bolts for the plate G. This plate has lateral slots g for the passage of these bolts, and by means of the slots f' and g the plate G may be readily adjusted to bring the die H in line with the machine. The die H is screwed into a central screw-threaded opening in the plate G. The cutting-edge h of the die should be placed as near the rear end of the splitting-knife and block E as will admit of a free discharge of the chips. The die internally and in cross section may be round, square, or of any form in which it is desired to make the dowel-pins, the round pins, however, being more commonly made. The rives

of wood are held by hand against a stationary gage, A², and are forced by the plunger against the knife C, splitting off the blank. The next blank forces the preceding blank 5 through the die, from the rear of which latter the finished dowel pins are discharged from the machine.

The device is simple and easily adjusted for different-sized dowel-pins, different dies of course being required for the different-sized pins.

In place of making the arm E elastic, it might be pivoted loosely and be made to accomplish the same end.

15 What I claim is—

1. In a machine for making dowel-pins, the combination, with a finishing-die, a splitting-knife set substantially parallel with the axial line of the die, a suitable bed, and reciprocating plunger, of a guide-block, the same being notched to engage two sides of the blank, and springs, respectively, for pressing the guide-block toward the knife and toward the bed-plate, substantially as set forth.

2. In a machine for making dowel-pins, the combination, with a bed-plate, a plunger mounted thereon, a splitting-knife, and notched guide-block yieldingly held in position, of a supporting plate, a finishing-die secured there- 30 to, and the flange integral with or rigidly secured to the bed-plate, the said plate and flange having respectively elongated holes at right angles to each other for the passage of the securing-bolts, substantially as set forth.

3. In a machine for making dowel-pins, the 35 combination, with a bed-plate having recesses a and a', made on opposite sides of the plate, of a splitting-knife and arm, D, secured in the respective recesses, said knife being set substantially parallel with the axial line of the 40 finishing-die, of a guide-block notched to engage the blank on two sides, said block being yieldingly held in position by springs that respectively press the guide-block downward and forward, the springs being adjustably supported from the said arm D, substantially as set forth.

4. The combination, with a bed-plate, a splitting-knife, a finishing-die, and a reciprocating plunger, of the block E, yieldingly secured to the bed-plate, and springs for pressing the block downward and laterally.

5. In a machine for making dowel-pins, the combination, with a finishing-die, a splitting-knife set substantially parallel with the axial 55 line of the die, and a device for guiding the blank, of springs arranged to press the guiding device downward and forward, substantially as set forth.

In testimony whereof I sign this specification 60 in the presence of two witnesses, this 7th day of May, 1886.

CLARENCE F. STEWART.
